CLAIM

The ornamental design for a coal and wood stove, substantially as shown and described.

DESCRIPTION

FIG. 1 is a front perspective view of a coal and wood stove, showing my new design;

FIG. 2 is a side perspective view thereof;

FIG. 3 is a rear perspective view thereof;

FIG. 4 is a top plan view thereof; and

FIG. 5 is a bottom plan view thereof.

The stove pipe has been shown fragmentarily in FIGS. 1—3 for convenience of illustration.
